UNITED STATES PATENT OFFICE

104,483

DESIGN FOR A RESTAURANT

Jesse J. Van Sandt and Alene Knox,
Los Angeles, Calif.

Application November 4, 1936, Serial No. 65,694

Term of patent 14 years

To all whom it may concern:

Be it known that we, Jesse J. Van Sandt and Alene Knox, citizens of the United States, residing at Los Angeles, in the county of Los Angeles and State of California, have invented a new, original, and ornamental Design for a Restaurant, of which the following is a specification, reference being had to the accompanying drawings, forming a part thereof.

In the drawings:

Fig. 1 is a front elevational view of a restaurant showing my new design.

Fig. 2 is a section on the line 2—2 of Fig. 1.

Fig. 3 is a side elevational view of the building showing the side opposite to that illustrated in Fig. 1.

We claim:

The ornamental design for a restaurant as shown.

JESSE J. VAN SANDT.
ALENE KNOX.
